UNITED STATES PATENT OFFICE.

JOHN GRANT, OF LOS ANGELES, CALIFORNIA, ASSIGNOR TO DUNN MANUFACTURING COMPANY, OF OXNARD, CALIFORNIA, A CORPORATION OF CALIFORNIA.

WELL ELEVATOR.

Application filed March 7, 1923. Serial No. 623,400.

This invention relates to well elevators, that is, to devices for handling, raising and lowering sections and strings of tubing, casing and piping, such as used in the drilling, boring and maintenance of oil and other wells, or for handling analogous objects or articles; and the invention has for its object to provide improved apparatus of this general character which will be superior in point of relative simplicity and inexpensiveness of construction, taken in conjunction with positiveness and reliability in operation, convenience in manipulation and use, durability and freedom from liability to get out of order or repair, and compactness in form, and which will be generally superior in efficiency and serviceability.

The invention constitutes an improvement upon or departure from the construction disclosed and claimed in other applications for patent for well elevators heretofore filed by me, among which is that filed February 14, 1923, Serial No. 619,000, for well elevators.

With the above and other objects in view, the invention consists in the novel and useful provision, formation, construction, combination, association and relative arrangement of parts, members and features, all as hereinafter described, shown in the drawing, and finally pointed out in claims.

In the drawing:

Figure 1 is a front elevation of a well elevator constructed and organized to embody the invention; suspension means or links for supporting the elevator and its load, and cooperating therewith, being shown in fragments, means for retaining the links in connection with the elevator being shown, and in operative position;

Figure 2 is a top plan view of the elevator shown in Figure 1, the same being partly in section upon the line 2—2, Figure 4;

Figure 3 is a vertical transverse sectional view taken upon the line 3—3, Figure 2, parts being in elevation, the means for retaining the suspension means or links being shown in operative position;

Figure 4 is a view similar to Figure 3, with the link-retaining means shown in inoperative position, and the links partly removed from the elevator;

Figure 5 is an end view of the elevator as shown in Figure 1;

Figure 6 is a perspective view of one mem-

ber of the link-retaining means in detached position;

Figure 7 is a detail transverse sectional view taken upon the line 7—7, Figure 1; and, Figure 8 is a detail transverse sectional view taken upon the line 8—8, Figure 1.

In Figures 1 and 2 are shown fragments of two sections or joints of tubing or casing, the same being connected together by a union or collar beneath which the elevator is applied.

Corresponding parts in all the figures are designated by the same reference characters.

Referring with particularity to the drawing, I have shown at A the body portion of a well elevator which, as shown in Figure 2, is curved or bowed to partially surround the casing or tubing B, of which two joints or sections are shown in Figures 1, 2, 3 and 4, the same being provided with a union or "collar" C for uniting such joints or sections together, the elevator body A being applied beneath such union or collar, to support the "string" or series of joints or tubing or casing sections. The body A preferably may surround the casing or tubing for more than half its superficial area, so that the major portion of the collar rests upon the body A; the open side of the body A being adapted to be closed by a gate or the like D, which may be hinged, as at d, at one side, to one side

or terminal portion of the body A, and the free end of which gate D may be provided with locking means e for cooperating with the other terminal portion of the body A, or an extension thereof, to retain the tubing or casing B within the elevator, and surrounded by its body and such gate. This prevents displacement of the elevator from the tubing or casing, or escape of the casing or tubing laterally from the elevator. All of these features of the general elevator construction are not involved in the present invention, which relates in substance to means

E for releasably retaining in position suspension means comprising a link or links or other substitute or equivalent devices f applied in connection with the elevator body A or end extensions 7 and 8 thereon, which end extensions are preferably diametrically opposed to each other. The means E preferably comprise two members g and h respectively, which cooperate with the respective links f, such members g and h being capable

of movement into and out of position to retain the respective links in working positions. It will be understood that such links *f* are suspended from a hook in the derrick of the well, or otherwise, and such suspension is not concerned specifically in the present invention.

In the particular form shown in the drawing, each of the members *g* and *h* of the means *E* is mounted to play substantially vertically in the respective extension 7 or 8 of the body *A*, and comprises spaced inner and outer substantially vertical limbs 9 and 10 respectively, connected by a top transverse or substantially horizontal member 11, together with a bottom and substantially horizontal member 12. Each extension 7 and 8 is provided with a substantially vertical bore 13 adjacent the body *A* within which plays the limb 10, and the outer end portion of each extension 7 or 8 is bifurcated, as at 9^a in the upper portion, to embrace and accommodate the vertical limb 9, and is bifurcated at the lower portion, as at 12^a to accommodate the lower limb or foot 12 of the respective member *g* or *h*, such accommodation and reception in each case providing for vertical play of the respective member *g* or *h*, and each extension 7 and 8 being slotted at the top, as shown in the broken away portion at 11^a, to accommodate the top limb 11 in part, when the respective member *g* or *h* is in lowered position, as shown in Figures 1 and 3. Each extension is cut away at its end portion inwardly to provide a curved seat or socket 7^a or 8^a for the respective link *f*, and further to provide a passage-way 7^b or 8^b to permit and accommodate removal of the link from such curved seat 7^a or 8^a, such seats and passage-ways providing for a link-accommodation, both in use, introduction and withdrawal of the suspension means. When the members *g* and *h* are in lowered position the vertical limbs 9 at their lower extremities in part close the passage-ways 7^b and 8^b; or at least to an extent which prevents escape or displacement of the links outwardly through said passage-ways, even if they be lowered from their seats 7^a and 8^a, the passage-ways at their inner terminal portions being of greater vertical dimensions, to include the curved formations of said seats, said seats being above the inner end portions of such passage-ways. When such members *g* and *h* are lowered as aforesaid, the base or foot members or limbs 12 are projected beneath the furcations 12^b of the bifurcated portions 12^a in part or in whole, so as to present themselves for contact with the derrick floor, or other object or objects, so that said members *g* and *h* may be raised, causing the vertical limbs 10 to rise in the bores 13, the transverse limbs 11 to rise in the slots 11^a, and the vertical limbs 9 to rise between the furcations 9^b of the

bifurcated portions 9^a; and this permits the lower ends of the links *f* to be displaced or removed from the extensions 7 and 8 outwardly, as illustrated in Figure 4, so that they may be applied to another elevator. It will be understood, however, that the members *g* and *h* may be manually or otherwise voluntarily operated, if desired. When the members *g* and *h* are held in raised position the links *f* may be passed through the passage-ways 7^b and 8^b and brought into the seats 7^a and 8^a, whereupon said members may be lowered and the passage-ways in part or in whole closed to retain the links in position.

As in the case of the inventions disclosed in said other applications, this invention provides for quick and convenient, or automatic, operation of the means for retaining the suspension means in position, and when the elevator rests upon the derrick floor, or the foot members 12 contact with some object or objects, holding the members *g* and *h* raised, they are in position to admit links, which are immediately retained from release or displacement as soon as the links and elevator are raised. Great saving of time and labor, which is very material in the modern fast drilling practice, results in the use of this invention. The members *g* and *h* are limited in their vertical or substantially vertical play by the engagement of the foot members 12 and transverse members 11 with the extensions 7 and 8, in the former case by shoulders 12^c, and in the latter case by the bottoms of the slots or channels 11^a. In assembling the members *g* and *h* the foot portions or limbs 12 may be connected with the lower ends of the vertical limbs 10 by transverse detachable pins 14.

It is obvious that many changes and variations may be made in departure from the specific construction and the mode of operation hereinabove described, and indicated and disclosed in the drawing, without departing from the true spirit of the invention.

One important feature of the present invention consists in the fact that the bifurcation 12^a of each extension 7 and 8 may be initially manufactured with extra length or dimension in projection from the body *A*, and may thereafter be cut down to just the desired dimensions for sitting across the well hole in the derrick floor.

Having thus disclosed my invention, I claim and desire to secure by Letters Patent:

1. Improvements of the character disclosed, comprising a body adapted to be applied to work, suspension means for the same, and means for retaining such suspension means in association with the body; said latter means being slidably associated with the body; the body being provided with a seat for the suspension means and with a

passage-way providing for access to said seat, and said slidable means being adapted when in one position to obstruct said passage-way; said slidable means being provided with a part adapted to be projected into position to cause movement of said slidable means upon contact with an object.

2. Improvements of the character disclosed, comprising a body adapted to be applied to work, suspension means for the same, and means for retaining such suspension means in association with the body; said latter means being slidably associated with the body; the body being provided with a seat for the suspension means and with a passage-way providing for access to said seat, and said slidable means being adapted when in one position to obstruct said passage-way; said slidable means comprising spaced limbs, a transverse limb connecting the same, and a foot portion adapted for contact with an object and connected with one of said spaced limbs.

3. Improvements of the character disclosed, comprising a body adapted to be applied to work, suspension means for the same, and means for retaining such suspension means in association with the body; said latter means being slidably associated with the body; said body being provided with an extension with which said suspension means is directly associated and with which is likewise associated said slidable means; said extension being substantially vertically bifurcated, and said slidable means comprising connected substantially vertical and substantially horizontal parts accommodated by such bifurcation.

4. Improvements of the character disclosed, comprising a body adapted to be ap-

plied to work, suspension means for the same, and means for retaining such suspension means in association with the body; said latter means being slidably associated with the body; said body being provided with an extension with which said suspension means is directly associated and with which is likewise associated said slidable means; said extension being substantially vertically bifurcated, and said slidable means comprising connected substantially vertical and substantially horizontal parts accommodated by such bifurcation; said extension being provided with a substantially vertical bore, and said slidable means including a substantially vertical limb whereby said other portions of said means are connected and being mounted to play in said bore.

5. A device of the character disclosed, comprising a body adapted to be applied to work, suspension means for the body, and means slidably associated with the body for maintaining the suspension means to the body when the body is in one position and permitting a releasing of the suspension means when the body is in a second position.

6. Improvements of the character disclosed, comprising a body adapted to be applied to work, suspension means for the same, and means for retaining such suspension means in association with the body; said latter means being slidably associated with the body; said slidable means being provided with a part adapted to cause movement thereof to release the suspension means when the slidable means contacts with an object.

In testimony whereof, I have signed my name to this specification.

JOHN GRANT.
